UNITED STATES PATENT OFFICE.

CHARLES F. MATZ, MICHAEL G. MATZ, AND BERNARD V. KERPER, OF DUBUQUE, IOWA.

HARROW.

1,355,494.

Specification of Letters Patent. Patented Oct. 12, 1920.

Application filed August 2, 1919. Serial No. 314,823.

To all whom it may concern:

Be it known that we, CHARLES F. MATZ, MICHAEL G. MATZ, and BERNARD V. KERPER, citizens of the United States, residing at Dubuque, in the county of Dubuque and State of Iowa, have invented certain new and useful Improvements in Harrows, of which the following is a specification.

Our invention relates to that class of harrows in which the ground-engaging member consists of a continuous spiral ribbon of metal and the object of the invention is to improve the construction so as to minimize the cost and facilitate the assembling of the parts while at the same time obtaining superior results from the use of the harrow.

The invention is illustrated in the accompanying drawings, in which—

Figure 1 is a plan view of a portion of a harrow constructed in accordance with our present invention;

Fig. 2 is a central longitudinal section;

Fig. 3 is an enlarged section through one of the gangs or spirals;

Fig. 4 is a detail perspective view of the connection between the draft-applying members and the inner ends of the spiral gangs;

Fig. 5 is a detail perspective view of the connection between the inner end of the spiral ribbon and the inner end of the axle;

Fig. 6 is a similar view of the connection at the outer end of the spiral;

Fig. 7 is a detail perspective view of the support for one of the intermediate spokes of the spiral;

Fig. 8 is a detail perspective view of the device employed for applying draft to the outer end of the spiral gang;

Fig. 9 is a detail perspective view of a bushing or sleeve which is employed to close the end of the tube fitted around the axle;

Fig. 10 is a perspective view of the parts of a latch employed to hold the spiral gangs in a set angular position;

Fig. 11 is a detail section showing different forms of ribbons.

The frame of the harrow consists essentially of a draft tongue 1, transverse beams 2 and 3 secured, respectively, to the upper and lower sides of the tongue adjacent the rear end thereof, and braces 4 secured to the tongue and to the said beams. A spring standard 5 is secured to the rear end of the tongue and carries a seat 6. On the under side of the tongue at the rear end thereof is secured a bracket 7 having spaced depend-

ing arms between which a roller 8 is mounted to be engaged by the upper edges of the draft bars 9. The bracket 7 is provided with a plurality of openings 10 in any one of which a shouldered pin 11 may be inserted to carry the roller 8, the shoulders of the pin engaging against the inner faces of the side members of the bracket so that said side members may be set close together without binding the roller in a well understood manner. The draft bars 9, as shown most clearly in Fig. 2, extend rearwardly beyond the tongue 1 and are then turned upwardly and formed into arches 12 having their extremities 13 disposed in the vertical plane of the axles and inserted through vertical openings in the nuts 14 which are threaded onto the inner ends of the axles 15, as clearly shown in Fig. 3. The rear ends of the arches 12 are engaged in a bail or link 16 so that the spreading apart of the draft bars will be rendered negligible and consequently the uncultivated space between the two gangs or spirals will be minimized. The front ends of the draft bars 9 are pivoted to the lower end of a lever 17 which extends through a longitudinal slot in the tongue 1 and is fulcrumed upon a holding rack 18 secured rigidly upon the upper side of the tongue. Upon the side of the lever 17 is slidably fitted a latch 19 adapted to engage the rack 18 and controlled by a handle 20 at the upper end of the lever and connected with the latch by a link 21. The latch is constructed with a longitudinal slot 22 to engage over a boss 23 on the inner face of one wall of a keeper 24 which is secured on the side of the lever 17 by a bolt inserted through a threaded opening in the said boss. It will be readily understood that the sides of the latch fit between the side edges of the boss 23 and the side flanges of the keeper so that it is held to a rectilinear path and will always be in proper position to engage the rack 18. A spring 25 playing between the boss 23 and the lower wall of the slot 22 tends to normally hold the latch in engagement with the rack so that when the lever has been adjusted to set the spiral gangs the latch will automatically engage the rack and hold the spirals in the set position.

Each axle 15 is a bar having threaded extremities and surrounded by a pipe or tube 26 which may be filled with oil or other lubricant, the opening for the lubricant be-

ing normally closed by a plug 27. Upon the outer threaded extremity of the axle is fitted a nut 28 which is constructed with a vertical opening 29 to receive the rear downturned 5 end of a link or draft bar 31 which is pivoted at its front end to the beams 2 and 3 of the harrow frame. By referring to Fig. 8 more particularly, it will be noted that the vertical opening 29 is formed in an offset 32 10 on the front side of the nut or block 28 at the end thereof which receives the axle and a threaded opening 33 is formed in the said end of the nut or block to engage the threaded extremity of the axle. A second 15 vertical opening 34 is formed through the nut 28 at the outer side thereof to receive the stem 35 of a weight box support; the upper portion of said support being forked, as shown at 36, so as to be rigidly secured to 20 the outer end of the weight box 37. The inner end of the weight box is connected directly with the arch 12 of the respectively adjacent draft bar 9 by a bracket or angle bar 38, the said bracket or angle bar being 25 rigidly secured to the draft bar and pivotally connected with the end of the weight box so that while the inner end of the weight box will be held close to the draft bar in all 30 adjustments of the harrow the relative angular movement of the weight box will be readily accommodated without causing the inner ends of the gangs to unduly separate. It will also be readily noted upon reference to the dotted lines in Fig. 1 that when the 35 draft bars are adjusted rearwardly so as to set the spirals in an oblique position, the outer ends of the spirals will be drawn inwardly and the links 31 will swing about their pivotal connection with the harrow 40 frame and the axles so as to permit the outer ends of the spirals to move inwardly.

The ground-engaging member 39 is in the form of a continuous spiral metal ribbon having one edge sharpened so that it will 45 readily penetrate the soil. At intermediate points of the spiral, it is supported by spokes 40 which are rigidly secured at their outer ends to the spiral and have their inner ends secured in seats 41 provided in arms 42 extending from collars 43 which are secured upon the tube 26 inclosing the axle. At the inner end of the spiral, we provide two 50 spokes to firmly support the same and the inner ends of these spokes are secured in seats 44 formed in the outer faces of a bar 45, said bar being provided at its center with a circular boss 46 to fit around the tube 26 and constructed on the wall of its bore with an 55 annular rib 47 to abut the end of the tube, 60 as clearly shown in Fig. 3. This rib 47 is constructed with a notch 48 to receive a lug 49 on a bushing or thimble 50 which is inserted in the end of the tube 26 and fits closely around the axle 15, an annular flange 65 or head 51 being provided at the outer end

of the thimble to abut the rib 47, as clearly shown in Fig. 3, so that the thimble will effectually close the end of the tube 26 and prevent the entrance of dirt thereinto and also prevent the loss of lubricant therefrom. 70 The engagement of the lug 49 in the notch 48 will cause the thimble to rotate with the bracket 45 and the spiral so that the only wear will be between the thimble and the axle. The head or flange 51 prevents the 75 thimble being driven in beyond the rib 47 and also furnishes a wide bearing for the nut 14. At the outer end of the spiral, we also employ two spokes which are secured in seat 52 formed in the outer face of a bracket 80 53 which is provided at its center with a hub 54 projecting from both its sides. The inner end of the hub 54 is fitted over the outer end of the tube 26, as shown clearly in Fig. 3, and the outer end of the hub is provided with an inturned annular flange or rib 55 to abut the end of the said tube and also has a notch 56 to be engaged by the lug 49 on a second sleeve or bushing 50 which is fitted through the hub into the end of the 85 sleeve and fits closely around the axle. It will thus be seen that both ends of the tube 26 are effectually closed so that the loss of lubricant is prevented.

The spiral blade has its inner face flat, as 90 shown at *c*, but the outer face of the blade may be in one plane, as shown at *a* in Fig. 11, or it may be beveled through a portion of its width and then extend at a right angle to its inner thickened edge, as shown at *b* in 100 Fig. 11. We have found that a flat ground-engaging face is exceedingly advantageous for the reason that it penetrates the soil more readily than a dished or convex face and does not hold dirt as a concave face 105 does. Inasmuch as the working face of the belt does not hold the dirt it polishes more readily and, therefore, remains in an operative condition for a longer period than other forms of blades which are known to us. 110

From the foregoing description, taken in connection with the accompanying drawings, it will be seen that we have provided a strong, simple and durable harrow by the use of which the ground may be thoroughly 115 pulverized and the untreated surface reduced to a minimum. The rear ends of the draft bars are held together as they are adjusted rearwardly and, consequently, the inner ends of the spiral gangs are prevented 120 from moving apart and the pivotal connection of the outer draft links between the frame and the gangs readily accommodates the adjustment. The particular form of latch on the hand lever devised by us is 125 very efficient inasmuch as the latch is constantly held to the rack unless it is manually withdrawn when setting the lever and the parts are of such simple construction that they may be readily fitted together and 130

when assembled the latch will be effectually guided and the projecting spring housed and guarded against. The branched standard or support for the outer end of the weight box holds the same very firmly so that it cannot tilt but at the same time this support is capable of pivotal movement in the nut or block on the end of the axle so that possible relative movement between the weight box and the spiral will be accommodated. Moreover, by our present arrangement draft is applied directly to the nut or block on the outer end of the axle and also to the nut on the inner end of the axle and to the inner end of the weight box so that any tendency of the spiral to drag or yield to the ground is effectually overcome. The brackets employed to provide seats for the spokes at the ends of the spiral will very effectually brace the said spokes so that they will withstand the strain placed thereon and the mounting of these brackets is such that they will rotate with the bushings and the spiral without excessive frictional wear.

Having thus described the invention, what is claimed as new is:

1. In a spiral harrow, the combination of an axle, a sleeve encircling the axle, thimbles fitted around the axle and in the ends 30 of the sleeve, brackets abutting the ends of the sleeve and fitted around and locked to the thimbles, spokes secured to said brackets, and a spiral blade secured to and extending between the spokes of the two 35 brackets.

2. In a spiral harrow, the combination of an axle, a sleeve encircling the axle, a thimble fitted around the axle and in the end of the sleeve, a bracket having seats on its 40 outer face and provided with a hub portion fitting over the end of the sleeve and having an internal rib fitting between the end of the sleeve and the head of the thimble, said rib being provided with a notch to engage 45 a lug on the thimble, spokes secured in the seats of said bracket, and a blade carried by the spokes.

3. In a harrow, the combination of a harrow frame, a draft bar mounted thereon and 50 extending rearwardly therefrom, an axle, a blade mounted for rotation about the axle, a nut fitted on the inner end of the axle and having a vertical opening therethrough in which the downturned rear end of the 55 draft bar is received, a nut on the outer end of the axle having a forwardly projecting offset, and a link pivoted at its front end to the harrow frame and having its rear end downturned and pivotally engaged in said 60 offset.

4. In a harrow, the combination of a harrow frame, an axle, a blade mounted for rotation about the axle, nuts fitted on the ends of the axle, a draft bar mounted on

and extending rearwardly from the harrow 65 frame and having its rear end turned downwardly and engaged through the nut at one end of the axle, a draft link pivoted to the opposite end of the harrow frame and pivotally engaged in the nut on the adjacent 70 end of the axle, a standard having its lower end inserted through and supported in the last mentioned nut, a connecting bar secured to the draft bar adjacent the rear end thereof, and a weight carrier secured at one end 75 to the said standard and at its opposite end to said connecting bar.

5. In a harrow, the combination of a frame, a pair of draft bars mounted on the said frame and projecting rearwardly therefrom at the center thereof, means for adjusting said draft bars forwardly or rearwardly, links pivoted at their front ends to the outer ends of the frame, axle supports pivotally connected at their ends with the rear ends of the draft bars and the said links, respectively, axles carried by said supports, blades mounted for rotation about said axles, and a nonextensible connection 85 between the rear ends of the draft bars 90 whereby they will be maintained in substantial parallelism in all their adjusted positions.

6. In a harrow, the combination of a pair of gangs, draft bars connected with the inner adjacent ends of the gangs, means for supporting the outer end of the gangs and permitting relative inward movement thereof, means for shifting the draft bars longitudinally whereby to vary the angular relation of the gangs, and a link connecting the rear ends of the draft bars whereby to prevent separation of the adjacent ends of the gangs in their various positions.

7. In a harrow, the combination of a frame, ground-engaging members mounted in rear of the frame, supporting devices extending between the ends of the frame and the outer ends of the ground-engaging members, draft bars connected with the inner ends of the ground-engaging members and supported on the frame for movement in the direction of their length, an adjusting lever mounted on the frame and connected with the draft bars, a holding rack on the frame adjacent the lever, and a latch mounted on the lever and arranged to engage said rack, said latch being longitudinally slotted, a keeper extending over the latch and having a boss engaging the slot therein, and a spring disposed between the said boss and the lower end of the slot in the latch.

In testimony whereof we affix our signatures.

CHARLES F. MATZ. [L. S.]
MICHAEL G. MATZ. [L. S.]
BERNARD V. KERPER. [L. S.]
